UNITED STATES PATENT OFFICE.

HENRY A. WISE WOOD, OF NEW YORK, N. Y., ASSIGNOR, BY MESNE ASSIGNMENTS, TO
WOOD NEWSPAPER MACHINERY CORPORATION, OF NEW YORK, N. Y., A CORPORA-
TION OF VIRGINIA.

PAPER-PIN HOLDING AND ADJUSTING DEVICE.

Specification of Letters Patent. Patented Feb. 15, 1916.

1,171,489.

Application filed June 16, 1913. Serial No. 773,916.

To all whom it may concern:

Be it known that I, HENRY A. WISE Wood, a citizen of the United States, residing at New York, in the county of New York and State of New York, have invented a new and useful Paper-Pin Holding and Adjusting Device, of which the following is a specification.

This invention relates to the rotary folding cylinders of web printing presses and the principal objects thereof are to provide a paper forwarding pin without screw threads, and yet having means whereby it can be removed and replaced easily and at small cost, and to provide simple and accessible means for adjusting each individual pin to any desired position, whereby the operator can regrind old pins that may have been damaged or slightly broken at the point, thus reducing his expense for pins.

The holding device is so arranged that the head of the pin, independently of its length, is always held firmly against a seating surface and the adjustment is arranged so that each individual pin can be adjusted as desired without affecting the simultaneous operation of all the pins by the usual pin rod.

The invention also involves improvements in details of construction and combinations of parts as will appear hereinafter.

Reference is to be had to the accompanying drawings, in which—

Figure 1 is a transverse sectional view of a portion of a folding and a cutting cylinder with a preferred embodiment of this invention applied to the former; Fig. 2 is a detail side view, partly in section, of the pin adjusting mechanism; Fig. 3 is an elevation of one of the pin adjusting segments showing the adjusting and fastening screws removed a slight distance therefrom; Fig. 4 is an enlarged central sectional view of a pin-holding device; and Fig. 5 is an end view of the same.

The invention is shown as applied to a well known form of folding couple consisting of a cutting cylinder 10 and a folding cylinder 11. As usual, the cylinders have pin rods or shafts 12 extending longitudinally thereof and oscillatably supported on the cylinder. This rod is shown as provided with a plurality of a series of teeth 13 therearound so that it constitutes a plu-

rality of worms at these points. Surrounding the rod at each of these points is a segmental gear 14 constituting an adjustable pin operating device. This gear is split at one side and is secured to the rod by means of a fastening screw 15. These gears are spaced apart by a series of sleeves 16 surrounding the rod.

For the purpose of adjusting each segmental gear individually when the screw 15 is loosened, each of these segmental gears is provided with a worm 17 meshing with the teeth 13. By turning this worm it is obvious that each gear can be shifted back or forth as desired independently of the others to micrometrically adjust each pin independently.

As is usually the case, the pin holder 20 is mounted in a passage in the cylinder so as to be moved longitudinally. It is provided with a rack 21 fitting the teeth of the segmental gear 14 for this purpose. It is obvious that when the gear is adjusted back and forth the pin holder also will be adjusted. In the end of this holder 20 is a central longitudinal socket 22 which is provided with screw threads and has a conical seat 23 at the bottom. This seat is for receiving the head 24 of the paper pin 25. This pin is smooth instead of screw threaded, as usual. It extends out centrally beyond the end of the socket. For the purpose of holding this pin firmly and simply a nut 26 is provided having a head 27 at the end and a longitudinal smooth perforation for receiving the pin. When it is desired to remove the pin the nut is unscrewed from the socket, the pin replaced by another, and the nut again screwed into the socket. The holder 20, of course, is locked against turning by contact with the segmental gear 14. The nut engages under the bottom of the head of the pin and forces the head to its seat in the bottom of the socket, thus securely holding it in position.

It will be seen from the description given that this mechanism affords an exceedingly simple, inexpensive and convenient method of clamping a pin independently of its length and adjusting it individually so that the operation of the pin rod will cause all the pins to operate accurately whatever their lengths. At the same time, the nut 26 is screw-threaded once for all, while the pins

are made plain. It is the pins that break and wear. This, clearly, therefore is a material economy over the usual construction which requires the threading of each pin.

Although I have illustrated and described only a single embodiment of the invention and shown only a single application thereof, I am aware of the fact that many modifications can be made therein by any person skilled in the art without departing from the scope of the invention as expressed in the claims. Therefore, I do not wish to be limited in these respects, but

15. What I do claim is:—

1. In a paper folding device, the combination with the cylinder, of a pin operating device carried thereby, means connected with said device for simultaneously operating a plurality of paper holding pins, and means connected with said device for individually adjusting each pin with respect to the device, said device being provided with means at intervals for coöoperating with said adjusting means.

2. In a paper folding device, the combination with the cylinder, of an oscillatable pin operating rod carried thereby, a plurality of means connected with said rod for simultaneously operating a plurality of paper holding pins, means connected with said rod for individually adjusting each pin micro-metrically with respect to the rod, and independent means for clamping the operating devices in adjusted positions on the rod.

3. In a paper folding device, the combination with the cylinder, of a pin operating rod carried thereby, a plurality of means connected with said rod for simultaneously operating a plurality of paper holding pins, a series of teeth on the rod at separated points, and a worm connected with each pin operating device for engaging said teeth and moving each pin operating device, individually with respect to the rod.

4. The combination with a cylinder, of a longitudinal rod thereon having a series of circumferential teeth, a member rotatably mounted on the rod, means supported by said member and engaging said teeth for adjusting said member about the rod, means for clamping the member to the rod in its adjusted positions, a movable pin holder,

and means for transmitting the motion of said member to the holder.

5. The combination with a cylinder, of a rotatable rod thereon having a plurality of series of teeth thereon, a plurality of segmental gears each rotatably mounted on the rod, means for adjusting each of said gears about the rod, means for clamping the gears to the rod in their adjusted positions, and a longitudinally reciprocable pin holder having a rack thereon for engaging the teeth of one of said segmental gears, whereby said holder can be reciprocated and adjusted.

6. In a paper folding device, the combination with a cylinder, of a holder thereon, means for reciprocating the holder longitudinally, said holder having a socket in the end thereof for the end of a paper holding pin, and readily removable means entering said socket for holding the head of said pin in a definite position therein against said socket.

7. In a device of the character described, the combination with a holder having a screw-threaded axial socket in the end, and a nut fitting said screw-threaded socket and having a passage therethrough, of a smooth, headed pin extending through said passage.

8. As an article of manufacture, a holder for a paper pin having a screw-threaded socket, and a nut having a passage therethrough for the pin and adapted to be screwed into said socket to hold the head of the pin therein.

9. As an article of manufacture, a holder for a paper pin having a screw threaded socket in the end thereof and provided with a seat at the bottom of said socket, a smooth pin having a head fitting said seat and adapted to project from the seat through the socket, and a nut fitting the screw threads in the socket and having a passage therethrough for the pin and an end adapted to fit under the head of the pin to hold it against said seat.

In testimony whereof I have hereunto set my hand, in the presence of two subscribing witnesses.

HENRY A. WISE WOOD.
